UNITED STATES PATENT OFFICE.

JOHN LOFTUS, OF ALBANY, NEW YORK, ASSIGNOR OF ONE-HALF TO
PETER KINNEAR, OF SAME PLACE.

FEED-WATER INJECTOR.

SPECIFICATION forming part of Letters Patent No. 311,500, dated February 3, 1885.

Application filed April 11, 1883. (Model.)

To all whom it may concern:

Be it known that I, JOHN LOFTUS, of the city and county of Albany, in the State of New York, have invented certain new and 5 useful Improvements in Feed - Water Injectors, of which the following is a specification.

My invention relates to improvements on the feed-water injector for which Letters Patent No. 247,464 of the United States were 10 granted to me on the 20th day of September, 1881; and the object of my present improvements is to simplify the construction of the device, and to render its action more certain and effective. This object I attain by means 15 of the mechanism illustrated in the accompanying drawings, which form a part of this specification, and in which—

Figure 1 is a longitudinal section of my improved injector; Fig. 2, a plan view of the 20 same; Fig. 3, an enlarged longitudinal section of the bushing or combining-tube; and Figs. 4 and 5 are respectively a side elevation 25 and an end elevation of the same.

As represented in the drawings, A is the 25 body-piece of the injector, made in cylindrical form, and having a branch, a, for the induction water-pipe connection depending from its under side, and two connecting valve-chambers, a' and a'', formed on its upper side. In 30 the bore of said body-piece, adjacent to the rear side of the opening in the branch a, an annular flange, a³, is formed for the purpose of forming the water-chamber B. A longitudinal opening, C, is made through the center of 35 the flange a³, which opening has an expanded mouth, c, that is turned toward the chamber B. A second annular flange or rib, D, that is formed in the bore of the body - piece A, between the valve-openings which lead into 40 the valve - chambers a' and a'', separates the vacuum-chamber E from the chamber F. The flange D is bored out to receive a removable bushing, G, which is fitted to slide easily 45 therein. The said bushing, which constitutes the combining-tube of my device, contains a 50 tapered longitudinal opening, g, through its axial center, and the largest end of said opening is turned toward the opening C. A slight flange, g', on the body of said bushing G, or 55 any equivalent means, prevents the bushing

from entering the body-piece beyond its prescribed distance toward the flange a³. Wings or lugs g² on the rearmost end of the bushing G keep said bushing, should it be displaced by the pressure against its forward end, from 55 moving too far toward the discharging end of the injector. The spaces between said lugs give ample room for the passage of water therethrough when the water - relief valve is open. The bushing G is so fitted that it can 60 be readily removed from the body - piece A through the discharging end of the injector. Thereby the interior of the body-piece is rendered readily accessible for the removal of any dirt or other obstructing matter that may 65 become lodged therein, and for the renewal of the bushing when it is worn or otherwise impaired by use, or the substitution of a bushing which contains a different-sized opening, can be effected without difficulty. A bush- 70 ing, H, is fitted to screw into the forward or receiving end of the body - piece A. Said bushing is provided with a jam-nut, h, whereby the bushing is secured in place after it has been adjusted to the required distance into 75 the chamber B. The outer end of the bushing H is furnished with the usual means for attaching the steam-supply pipe thereto, and on its inner end a nozzle, h', is formed. Said nozzle has a tapered longitudinal opening, h², 80 bored through its axis, to range in line with the opening C. The end of said nozzle may be adjusted to enter the mouth c of the opening C when occasion requires such adjustment. 85

Over the vacuum - chamber E there is a steam-relief valve, e, that is arranged to close the opening which leads into the valve-chamber a'. Said valve-chamber has an escape-opening, a⁴, to which an escape-pipe may be 90 connected for the purpose of conducting away any steam or water that may escape therethrough.

In the top of the chamber F an opening is formed to lead into the valve-chamber a'', and 95 into said opening the water - relief valve f is fitted, so as to close the communication between the chamber F and valve-chamber a''.

The valve-chambers a' and a'' are connected by means of the passage a⁵ in such manner 100

that the single escape-opening a^4 will serve for both of said chambers. A bushing, I, is screwed into rearmost or discharge end of the body-piece A, and the outer end of the said bushing is provided with the usual means for connecting thereto the feed-water pipe that leads from the injector to the boiler. The inner end of said bushing is provided with a recess for receiving a supplementary bushing or reducer, J. The bushing J is removable from its recess in order to substitute bushings with different size of opening, and so as to facilitate the renewal of such bushings whenever their openings have become worn or otherwise impaired by use.

The operation of my injector having been fully described in Letters Patent No. 247,464, hereinbefore referred to, a repetition of it herein is unnecessary.

I claim as my invention—

1. In a feed-water injector, a removable combining-tube or bushing, G, fixed in the annular flange D of the body-piece A, and provided at its rearmost end with wings or lugs g^2 , as and for the purpose herein specified. 20
2. In a feed-water injector, the combination, with the bushing I, contained in the discharge end of the body-piece A, of the removable bushing or reducer J, inserted in the inner end of the bushing I, as and for the purpose 25 herein specified. 30

JOHN LOFTUS.
